UNITED STATES PATENT OFFICE.

LEON B. YEISER, OF CLEVELAND, OHIO.

WASTE AND OVERFLOW ATTACHMENT FOR BATHTUBS.

1,427,567.

Specification of Letters Patent. Patented Aug. 29, 1922.

Application filed May 29, 1919, Serial No. 300,695. Renewed March 20, 1922. Serial No. 545,343.

To all whom it may concern:

Be it known that LEON B. YEISER, citizen of the United States, residing at Cleveland, in the county of Cuyahoga and State of Ohio, has invented certain new and useful Improvements in a Waste and Overflow Attachment for Bathtubs, of which the following is a specification.

My invention pertains to a waste and overflow attachment for bath tubs, and the invention involves an organization of parts in which a single rotary valve is adapted to control the outflow of waste water from the tub, and the overflow is adapted to pass through the same valve. As designed, the location and construction of this valve permits its removal from the overflow pipe without disassembly of the pipe fittings, and adjustments in length and placement of the pipes may be effected with considerable accommodation thereto of the valve operating connections. The overflow fitting is also particularly constructed to be secured to the tub by a set of separable members through which the water may be delivered into the tub. The waste valve may also be located remotely from the waste and overflow openings in the tub and the valve handle arranged in an accessible place opposite the rim of the tub or in one corner of the tub.

In the drawings accompanying this application, Fig. 1 is a cross section of a bath tub equipped with my improvements, and Fig. 2 is a vertical section on a larger scale of the combined overflow fitting and water delivering connection on line 2-2, Fig. 1. Fig. 3 is a side elevation of the water delivery elbow which passes through the overflow fitting and is used to secure the fitting in place upon the tub. Fig. 4 is a top view of one end of a tub showing the combined cold and hot water valve with the waste and overflow fittings and the controlling valve for the waste water. Fig. 5 is an enlarged view, mainly in section, of the waste and overflow pipes and fittings and waste valve assembled, but with only portions of the tub disclosed. Fig. 6 is a view corresponding to Fig. 1 but showing a modification of the invention. Fig. 7 is a central section of the jointed fitting member for the horizontal waste pipe and angle overflow pipe shown in Fig. 6. Fig. 8 is a plan view of part shown in Fig. 7.

As shown, the invention comprises a bath tub 2 having a rim 3, and in many tubs this

rim extends downwardly in the form of a vertical wall or apron 4. One end wall of tubs of this description generally have three openings adapted to receive a pair of valves 60 or valve bodies and an overflow fitting, and in the present instance a combined hot and cold water valve is used which embodies two tubular extensions 5 and 6 which project through two of said openings into the interior of the tub and have separate valves with handles 7 and 8 adapted to control the delivery of hot and cold water, either independently or together.

The supply of hot and cold water is derived from separate hot and cold water pipes 9 and 9' which connect with the outer ends of the tubular extensions 5 and 6, and a single delivery pipe or member 10 of elbow shape conveys the water from a cross connecting passage 11 into a valved spout member 12 placed within the tub opposite a grille or perforated plate or disk 13. The horizontal leg of member 10 and the grille plate 13, together with a round hollow overflow fitting 14, occupy the third and larger opening in the end wall of the tub, and each of said members have flanges adapted to provide bearing surfaces whereby the several parts may be clamped together upon the tub 85 wall by screwing the spout member 12 upon the screw-threaded end of the horizontal leg of elbow member 10 until it engages the grille plate and draws the several parts together. The overflow fitting 14 has a flat 90 rear face 15 with a central opening adapted to receive the horizontal leg of member 10, and the round body portion of this fitting member has a short boss or extension 16 at one side adapted to provide a connection for 95 an overflow pipe 17, see Fig. 5.

As shown, pipe 17 is horizontally placed and extends to the left side of member 10 but the fitting member 14 is capable of being rotated around the horizontal leg of elbow 100 member 10 and the overflow pipe placed at the right side of the axis and the opposite side of the tub or even arranged to extend downwardly on perpendicular or inclined lines toward the bottom of the tub. The 105 length of pipe 17 may vary dependent upon the width of the tub or the distance that the vertical waste pipe 18 may happen to be located away or apart from the waste opening 19 in the bottom of the tub, and where waste 110 pipe 18 is placed in one corner of the tub the pipe 17 extends transversely of the tub

on a straight line from fitting member 14, and a slip joint connection is made with a T-fitting 20 forming part of the waste pipe 18. A short pipe section pipe 21 extends upwardly from T-fitting 20 and projects through an opening 22 in the rim of the tub. A flanged screw-cap 23 engages the upper end of section 21 and clamps down upon the rim. This cap has a central opening adapted to accommodate a square or flat-sided rod 24 having a handle 25 detachably affixed to its upper end in rotatable stop relation to a semi-circular lug 26 on the upper face of cap 23. Rod 24 is relatively long and extends downwardly through pipe section 21 and fitting 20 and also through a second pipe section 27 and a T-fitting 28. The upper end of pipe section 27 has a slip joint connection with the bottom end of fitting 20 and the lower end of said pipe section is screw-engaged with the upper end of T-fitting 28.

A tubular valve 29 is rotatably seated within fitting 28 and rod 24 has slidable engagement with a lateral lug 30 within said valve, and an opening 31 at the side of said valve is adapted to register with the horizontal passage in the lateral portion 32 of fitting 28. This lateral portion is connected to the bottom waste opening 19 of the tub by a horizontal branch pipe 33 together with a waste fitting 34 which is clamped to the bottom of the tub by a screw-threaded strainer plate 35. A slip joint connection is preferably used between T-fitting 28 and horizontal pipe 33, and the several adjustable or slip-joint connections described comprise flanged union nuts and suitable gaskets adapted to provide fluid-tight joints.

In operation, handle 25 is in convenient reach of the user of the tub whether outside or inside of the tub and a partial turn of the handle will rotate valve 29 and either open or close the waste passage through pipe 33. However, the overflow through fitting member 14 and pipes 17 and 27, is not shut off by rotation of the valve because the valve is tubular and there is room for the overflow water to pass through the valve at either side of lug 30 and the water is free to escape through pipe 18 at all times. The valve may however be lifted entirely out of the vertical pipes whenever cap 23 is unscrewed, and the pipes can be examined or cleaned and the valve inspected and cleaned at any time.

The parts are readily assembled regardless of variations in the distances between the fitting members, and the vertical waste pipe may be located in either corner of the tub or directly at the end of the tub and adapted to extend through openings in the rim of the tub or to be placed entirely outside of said rim, and in making such connections the only thing the mechanic has to consider is the length of pipe to be used.

In Figs. 6, 7 and 8 I show an organization of parts corresponding in general with the structure hereinbefore described, but in lieu of placing overflow pipe 17 in a horizontal position, I place it at an angle or inclination relatively to the vertical waste pipe 18 and employ slightly modified fitting 20' to permit an angular connection to be made with pipe 17. Further, fitting 20' is screw-engaged directly with the upper end of the valve fitting 29' and these two fittings are thereby rotatably connected to permit pipes 17 and 33 respectively, to be adjusted and set in different angular relation. This arrangement of parts eliminates the need of pipe section 27 between fittings on the stand pipe, but requires a somewhat longer top section 21' as compared with pipe section 21 in Fig. 1.

What I claim is:

1. A bath tub having separate waste and overflow openings and outlet fittings therefor each having separate discharge pipes connected thereto and the overflow fitting being rotatably clamped opposite its opening, a single vertical waste pipe having fittings with which said discharge pipes are connected, and a valve within said vertical pipe adapted to control the outflow of waste water therefrom.

2. A bath tub having separate waste and overflow connections at different elevations, a vertical discharge pipe having separate fittings rotatably connected therewith and adjustable vertically with a slip joint at one of said fittings, a tubular valve rotatably mounted within the lower fitting, an operating rod in vertical adjustable connection with valve extending through said vertical pipe and the upper fitting, and a handle for said rod above the upper end of said vertical rod.

3. A bath tub having separate openings in its end and bottom and separate waste and overflow fittings extending through said openings, a single discharge pipe and branch pipes connecting said fittings with said discharge pipe, and the overflow fitting being rotatably mounted in the opening in the end wall of the tub and having a water delivery member extending centrally through the rear thereof and into the tub.

4. A bath tub having a bottom waste connection and an opening in its end wall, a water delivery member extending through said opening into the tub, a chambered overflow fitting swiveled upon said delivery member and rotatably mounted within the opening in said tub, and a branch overflow pipe connected with said fitting.

5. A combined overflow fitting water delivery attachment for bath tubs comprising an angle member having a central passage and a chamber member having a rear wall with a central opening adapted to sleeve

over and rotatably engage one of the legs of said elbow and being provided with an outlet in its side wall and an intake opening at its front end.

- 5 6. A bath tub having a wall with an opening therein, a hollow overflow fitting having a front intake opening and a side outlet and a central rear opening, a water delivery member in bearing engagement with the rear 10 end of said fitting having a horizontal extension projecting through said rear opening and into the tub, a perforated plate sleeved upon said extension in clamping engagement with the tub wall, and a spout

member screw-engaged with said extension 15 in bearing engagement with said plate.

7. In a bath tub, a hot and cold water valve, an overflow fitting having a front intake opening and a side outlet, a water delivery elbow connected with said valves and 20 projecting into the tub, said fitting being sleeved loosely upon said elbow and rotatable in respect thereto and the tub, and means to clamp said fitting and elbow upon the tub.

Signed at Cleveland, in the county of 25 Cuyahoga, and State of Ohio, this 19th day of April, 1919.

LEON B. YEISER.
